UNITED STATES PATENT OFFICE

2,095,085

YIELDABLE BARRIER

Emerson D. Sawyer, Chicago, Ill.

Application December 21, 1936, Serial No. 116,945

12 Claims. (Cl. 39—1)

The invention relates to improvements in yielding barriers adapted and arranged to be extended across roadways, or the like, to prevent accidents at points of danger, the primary object of the present invention being to provide a barrier of the character indicated which is of simple construction and highly efficient in use, the present invention being an improvement upon that illustrated in my prior Patent No. 1,828,296.

Another object of the invention is the provision of an improved barrier construction of the character indicated so constructed and arranged as to render it possible to place the barrier net relatively close to the roadway while at the same time maintaining the operating parts or connections above the normal sidewalk level.

Other objects will appear hereinafter.

The invention consists in the combinations and arrangements of parts hereinafter described and claimed.

The invention will be best understood by reference to the accompanying drawings forming a part of this specification, and in which

Fig. 1 is a partial section taken through the lower portion of one of the columns of the barrier in a plane substantially parallel with the direction of the roadway;

Fig. 2 a section of the same taken at right angles thereto;

Fig. 3 an enlarged detailed section taken adjacent a supporting bracket secured to the under side of the carriage of the barrier;

Fig. 4 a section taken substantially on line 4—4 of Fig. 3;

Fig. 5 a section taken substantially on line 5—5 of Fig. 3;

Fig. 6 a face view of said supporting bracket with portions broken away or removed; and

Fig. 7 a view corresponding with the lower portion of Fig. 2 but showing a slightly modified form of construction.

The embodiment of the invention illustrated in the drawings comprises the usual carriage 10 mounted and arranged to reciprocate vertically in the usual column 11 and equipped with the usual guide rollers 12 running upon guide bars 13 on the side walls of said column. The carriage is provided with a tubular guide member or fair leader 14 cooperating with a grooved guide pulley or sheave 15 in said carriage and adapted and arranged to serve as guides or directing members for the lowermost payout cable 16 of the barrier construction. These parts are identical with the corresponding parts illustrated and de-

scribed in my said prior Patent No. 1,828,296 and require no further description here.

A supporting bracket 17 is secured, as shown, to the bottom of the carriage 10 to protrude through the usual slot in the column 11, said bracket being provided in its outer wall with a slot 19 open at its bottom and with cooperating sides 18 forming a passageway therethrough in registration with said slot. The bracket 17 is also provided at opposite sides with abutments 17' and 18' adapted and arranged to engage the inner sides of the outer wall of the column so as to transfer the outward horizontal resultant of an impact against the barrier to the outer wall of the column and thereby relieve the bracket 17 and carriage from such strain or shock.

A tubular guide member or fair leader 20 is arranged to be inserted in said passageway and slot. For this purpose the guide member is provided at its lower outer end with an enlarged head 21 projecting substantially horizontally and provided with notches 22 behind it to receive the sides of the bracket 17 to permit of the insertion of the lower end of said guide member in said slot 19, as shown. The lower outer corners 23 and the upper inner corners 24 of the notches 22 are rounded, as best shown in Fig. 3, so as to facilitate this insertion.

A suitable opening is provided in the bottom of the carriage 10 to permit the insertion of the upper end of the tubular guide 20 therethrough, and the upper end of said guide is provided with a guide tongue 25 adapted and arranged to project into the groove of the guide pulley or sheave 15 when said guide member is arranged in substantially tangential relation, so as to insure the proper passage of the payout cable 16 therethrough. The guide member 20 is provided with abutment shoulders 26 fitting snugly against the bottom of the carriage 10, and a locking bar 27 is secured by bolts 28 across the lower end of the slot 19 to lock the head 21 of the guide member 20 in position in said slot. A supporting abutment block 29 is secured in the bracket 17 by means of a cross pin 30, in position to abut against the lower side of the guide member 20, and thereby further secure the same in place. The abutment member 29 is provided with perforated ears 31 between which the upper end of an operating chain 32 is secured by means of a pin 33. The operating chain 32 connects with a sprocket 34 on a shaft 35 leading into a gear reducing mechanism 36 operable through the usual electric motor 37 to facilitate movements of the carriage 10 in the usual way.

As shown, the sprocket 34, speed reducing mechanism and motor 37, are mounted in the column above the sidewalk level 38, the roadway level being indicated at 39.

- 5 By this arrangement, the lower payout cable 16 of the barrier net is arranged to pass downwardly and outwardly through the bottom of the carriage and emerge from the column at a point below the guide rollers 12, so that the barrier net 10 will be positioned at a comparatively low elevation over the roadway level 39 and at the same time all of the operating mechanism for the carriage 10 located above the sidewalk level so as not to be interfered with by ice, snow, or debris 15 entering the lower portion of the column. In this way a barrier may be so mounted or positioned relatively to the roadway as to be low enough to contact with the lowermost substantial portions of an automobile or vehicle and at the same time 20 the operating parts and connections located high enough in the column so as to be free of danger of stoppage through ice, snow or accumulated debris.

The specific form and arrangement of parts 25 disclosed is a simple and effective one for the purpose.

In the modification illustrated in Fig. 7, a chain clip 31' is formed integral with one of the sides 18 of the bracket 17 at a point to the rear 30 and at a higher elevation than the abutment block 29 so that the operating chain 32 may be secured thereto, as shown. By this arrangement, the sprocket 34 may be moved back on the shaft 35 into registration with the clip 31', as shown, 35 thereby permitting the lowering of the guide 20, and consequently the lowermost payout cable, to a much lower level, and thereby causing the lowermost payout cable to emerge at a point below the level of the top of the motivating sprocket 40 34 and bringing the barrier net correspondingly closer to the top of the roadway, as will be readily understood.

While I have illustrated and described the preferred forms of construction for carrying my invention into effect, these are capable of variation and modification without departing from the spirit of the invention. I therefore do not wish to be limited to the precise details disclosed, but desire to avail myself of such variations and 50 modifications as fall within the scope of the appended claims.

I claim:

1. A yieldable barrier operating mechanism comprising a vertically movable carriage; a flexible payout and supporting element for the lower portion of the barrier net mounted in and arranged to pay out from said carriage; and guiding means for said element causing it to emerge from said mechanism at a point below the bottom 55 of the carriage.

2. A yieldable barrier operating mechanism comprising a vertically movable carriage; a flexible payout and supporting element for the lower portion of the barrier net mounted in and arranged to pay out from said carriage; and guiding means for said element arranged to guide it 60 downwardly and outwardly from said carriage.

3. A yieldable barrier operating mechanism comprising a vertically movable carriage; a flexible payout and supporting element for the lower portion of the barrier net mounted in and arranged to pay out from said carriage; and guiding means for said element arranged to guide it 70 first downwardly through the bottom of and then 75 outwardly from said carriage.

4. A yieldable barrier operating mechanism comprising a vertically movable carriage; a flexible payout and supporting element for the lower portion of the barrier net mounted in and arranged to pay out from said carriage; and an inclined tubular guide for said element mounted on and extending downwardly and outwardly through the bottom of said carriage. 5

5. A yieldable barrier operating mechanism comprising a vertically movable carriage; a flexible payout and supporting element for the lower portion of the barrier net mounted in and arranged to pay out from said carriage; a grooved guide sheave for said element mounted in the lower portion of said carriage; and an inclined 10 tubular guide for said element mounted on said carriage substantially tangential to said sheave and extending thence downwardly and outwardly through the bottom of said carriage. 15

6. A yieldable barrier operating mechanism comprising a vertically movable carriage; a flexible payout and supporting element for the lower portion of the barrier net mounted in and arranged to pay out from said carriage; a grooved 20 guide sheave for said element mounted in the lower portion of said carriage; and an inclined tubular guide for said element mounted on said carriage substantially tangential to said sheave and extending thence downwardly and outwardly 25 through the bottom of said carriage, the outer end of said tubular guide being turned substantially horizontally.

7. A yieldable barrier operating mechanism comprising a vertically movable carriage; a flexible payout and supporting element for the lower portion of the barrier net mounted in and arranged to pay out from said carriage; a grooved guide sheave for said element mounted in the lower portion of said carriage; an inclined tubular 30 guide for said element mounted on said carriage substantially tangential to said sheave and extending thence downwardly and outwardly through the bottom of said carriage, the outer end of said tubular guide being turned substantially horizontally. 35

8. A yieldable barrier operating mechanism comprising a vertically movable carriage; a flexible payout and supporting element for the lower portion of the barrier net mounted in and arranged to pay out from said carriage; motivating 40 means for said carriage connected with the bottom thereof; and guiding means for said element causing it to emerge from said mechanism at a point below the level of the lowermost point of normal contact between the carriage and column. 45

9. A yieldable barrier operating mechanism comprising a vertically movable carriage; a flexible payout and supporting element for the lower portion of the barrier net arranged to pay out from said carriage; motivating means for said carriage connected with the bottom thereof; and guiding means for said element causing it to emerge from said mechanism at a point below the level of the lowermost point of contact between the carriage and column. 55

10. A yieldable barrier operating mechanism comprising a vertically movable carriage; a flexible payout and supporting element for the lower portion of the barrier net arranged to pay out from said carriage; motivating means for said carriage connected with the bottom thereof; and guiding means for said element causing it to emerge from said mechanism at a point below the level of the top of the motivating means. 70

11. A yieldable barrier operating mechanism 75

comprising a vertically movable carriage; a flexible payout and supporting element for the lower portion of the barrier net mounted in and arranged to pay out from said carriage; a grooved 5 guide sheave for said element mounted in the lower portion of said carriage; a supporting bracket mounted on the outer portion of the bottom of said carriage, said bracket being provided with a slot in its outer face and a passageway 10 therethrough in registration with said slot; an inclined tubular guide for said element notched at its sides to fit into said slot, shaped and arranged to extend upwardly and inwardly through said passageway, there being an opening 15 in the bottom of the carriage to permit the passage of the upper end of said tubular guide into substantially tangential arrangement with said sheave; a guide tongue on the upper end of said tubular guide projecting into the groove in 20 said sheave; shoulders on the sides of said tubular guide abutting against the bottom of said carriage; and means for securing said guide in said bracket.

12. A yieldable barrier operating mechanism comprising a vertical movable carriage; a flexible payout and supporting element for the lower 25

portion of the barrier net mounted in and arranged to pay out from said carriage; a grooved guide sheave for said element mounted in the lower portion of said carriage; a supporting bracket mounted on the outer portion of the bottom of said carriage, said bracket being provided with a slot in its outer face and a passageway therethrough in registration with said slot; an inclined tubular guide for said element notched at 5 its sides to fit into said slot, shaped and arranged to extend upwardly and inwardly through said passageway, there being an opening in the bottom of the carriage to permit the passage of the upper end of said tubular guide into substantially tangential arrangement with said sheave; a guide 10 tongue on the upper end of said tubular guide projecting into the groove in said sheave; shoulders on the sides of said tubular guide abutting against the bottom of said carriage; a cross bar closing the lower end of the slot in said bracket 15 to support said tubular guide therein; an abutment member secured in said bracket below said tubular guide and supporting the same in said passageway; and an operating chain connection 20 with said abutment member. 25
